CLAIM

The ornamental design for an air pressure massager as shown and described.

DESCRIPTION

1. Air pressure massager

1.1 : Top

1.2 : Back

1.3 : Bottom

1.4 : Right

1.5 : Front

1.6 : Left

The device is an air pressure massager intended to temporarily relieve minor muscle aches and/or pains, and to temporarily increase circulation to the treated areas.

The broken lines in the drawings illustrate the portions of the air pressure massager that form no part of the claimed design.
